HAND SIGNAL LIGHT

Hubert N. Burgess, Rockford, Ill.

Application July 25, 1952, Serial No. 300,949

6 Claims. (Cl. 340—321)

1

This invention relates to a hand signal light intended for use by ushers in moving picture theaters and other places for signalling to a head usher at the door the number of vacant seats available, as well as to illuminate the floor in the vicinity of the vacant seats for the benefit of the incoming patrons.

I am aware that signal lights for this purpose have been devised before but they have not been adopted, evidently either because they did not function satisfactorily or because they were too complicated and expensive in construction. My experiments with the device of my invention convinced me that the problem is not simply that of satisfactorily signalling to the distant usher the number of seats available; it is also important that the device give just the amount of floor illumination needed, but no more, otherwise the signal light is a source of distraction to the surrounding audience and theater managers would not purchase such devices for that reason. It is, therefore, the principal object of my invention to provide a hand signal constructed and designed to meet the requirements mentioned and avoid the objections indicated.

The invention is illustrated in the accompanying drawing, in which—

Fig. 1 is a view partly in side elevation and partly in longitudinal section of a hand signal light made in accordance with my invention;

Fig. 2 is an end view, as indicated by the line 2—2 in Fig. 1; and

Fig. 3 is a cross-section on the line 3—3 of Fig. 1.

The same reference numerals are applied to corresponding parts throughout these views.

Referring to the drawing, the reference numeral 5 designates a flash-light of conventional design and construction having a bulb 6 in one end of the casing 7 disposed centrally with respect to a reflector 8 behind a lens 9 to project light forwardly along the axis of the casing 7 when the switch button 10 is moved to the "on" position, in the usual way. A silent push-button switch is connected in series with switch 10 so that the light is on only when the button 10 is depressed, that is, assuming switch 10 is turned on. In the conventional flash-light a flanged ring is threaded on the threaded end portion 14 of the casing 7 to retain the lens 9, but in the device of my invention, a ring 12 is provided in the form of a projecting collar disposed centrally on one end of a square housing 13 and soldered or otherwise suitably secured, as indicated at 14, to said end wall 15 in concentric relation to a circular opening 16 provided in the center of the end wall, and this ring threads onto the end of the casing 7 to fasten the housing 13 onto the flash-light casing and at the same time hold the lens 9 and reflector 8 and bulb 6 in place. Of

2

course, while the flash-light is detachable, that is only to permit replacement of a burned out bulb in the present design. I may provide the central opening 16 in the end wall 15 and then, instead of collar 12, provide any other suitable or preferred means of detachably fastening a flash-light rigidly onto the end of the housing with the lens 9 similarly disposed with respect to the opening 16, so that the signal light could be sold as a separate unit, namely, as an attachment applicable to existing flash-lights, instead of as an integral or assembled part of a unit with the flash-light, as herein disclosed.

The square housing 13 is open at the end remote from the wall 15, as indicated at 17, and a square cover 18 is provided to close this open end. On the four side walls 19, 20, 21 and 22 of the housing 13, numbers 1 to 4 are provided, respectively, as indicated at 23, by cut-outs, these numbers being preferably arranged so that they are upright when the flash-light 5 is directed downwardly, as indicated by the number 3 appearing in Fig. 1. The cover 18 has a zero provided in the center thereof, as indicated at 24, also by cut-outs. The usher in using the light to signal will, of course, turn the flash-light 5 around so as to turn the housing 13 to indicate to the distant usher the number of seats vacant, and, when there are no vacancies, the usher will raise the flash-light to a substantially horizontal position in the direction of the distant usher, showing the zero. All of these numbers are arranged to be illuminated by indirect lighting from the lens 9 of the flash-light. A square tube 25 is mounted inside the housing 13 centrally thereof by means of lugs 26 that extend radially from one end of the tube and are spot-welded or otherwise suitably secured at their extremities 27 to the side walls 19 and 28 of the housing 13, leaving ample space between the inner end of the tube 25 and the end wall 15 of the housing 13, as indicated at 28, for indirect illumination of the cut-out numbers 1 to 4 in the side walls 19—22, while most of the light from the flash-light will be conducted through the tube 25 toward the cover 18. The tube 25 is spaced farther inwardly from the cover 18 than it is from the end wall 15 and in this space a square plate 29 is mounted transversely in relation to the outer end of tube 25, the same having lugs 30 extending radially from opposite sides thereof and secured at their extremities 31 to the side walls 21 and 22 of the housing 13, as by spot-welding. The plate 29, being spaced from the end of tube 25, as indicated at 32, and also spaced from the side walls 19—22 of the housing 13, as indicated at 33, and also spaced from the cover 18, as indicated at 34, intercepts the light coming through the tube 25 so as to permit only indirect lighting of the zero 24 provided in the center of cover 18.

The plate also reflects light toward the cut-outs 23 to give better illumination of numbers 1 to 4. A small circular hole 35 is preferably provided in the center of the plate 29 in line with a smaller circular hole 36 to allow a certain amount of more or less direct lighting of the floor through the hole 36 and the cut-outs 24 in the cover 18, because floor illumination is important, especially in fully darkened moving picture theaters, to enable patrons to see where they are walking when the usher directs them to their seats. The holes 35 and 36 are carefully gauged as to diameter in relation to both the bore of tube 25 and the dimensions of the zero cut-outs 24 to enable good signalling with the zero and yet provide just the desired amount of floor illumination, but not too much.

It is believed the foregoing description conveys a good understanding of the objects and advantages of my invention. The appended claims have been drawn to cover all legitimate modifications and adaptations.

I claim:

1. In a portable hand signal light, a housing of elongated form having side walls uniformly spaced from a longitudinal axis, said housing also having opposed end walls, the side walls having openings provided therein defining signal legends adapted to be illuminated on their inner side, a light source such as a flash-light on one end wall of said housing arranged to project light into said housing substantially along the longitudinal axis, said flash-light providing an elongated handle projecting from the said end wall on said longitudinal axis, the other end wall of said housing remote from the light source having openings provided therein defining another signal legend adapted to be illuminated from inside said housing, a tube mounted in said housing on the longitudinal axis and adapted to conduct the major portion of the light from said flash-light to the other end of said housing said tube being spaced at its ends from the end walls and being also spaced from the side walls so as to allow only indirect lighting of the signal legend openings in said side walls, and a plate mounted in said housing transversely relative to the outer end of said tube in spaced parallel relation between the outer end of said tube and the adjacent end wall so as to provide indirect lighting of the signal legend openings in said end wall and to reflect light toward the legend openings in said side walls.

2. A hand signal light as set forth in claim 1, wherein said plate has a central opening provided therein of small dimensions in relation to the bore of the tube, through which is permitted a predetermined amount of direct illumination of the legend openings in the end wall.

3. A hand signal light as set forth in claim 1, wherein said plate has a central opening provided therein of small dimensions in relation to the bore of the tube, through which is permitted a predetermined amount of direct illumination of the legend openings in the end wall, the legend openings in the end wall defining a zero ("0") that is large in dimensions in relation to the opening in the plate and located substantially in concentric relation thereto, whereby to permit medium good direct floor illumination through the end wall in addition to good illumination of the zero for signal purposes.

4. A hand signal light as set forth in claim 1, wherein said plate has a central opening provided

therein of small dimensions in relation to the bore of the tube, and wherein said end wall has a central opening provided therein of still smaller size in concentric relation to the plate opening, whereby a predetermined amount of direct illumination is permitted through said end wall.

5. In a portable hand signal light, a housing of elongated form having side walls uniformly spaced from a longitudinal axis, said housing also having opposed end walls, the side walls having openings provided therein defining signal legends adapted to be illuminated on their inner side, one end wall having a central opening provided therein and, around said opening, means for detachably securing in rigid relation to the housing and in concentric relation to the opening the lens end of a flash-light having an elongated casting whereby the flash-light is adapted to provide an elongated handle projecting from the said end wall on said longitudinal axis and whereby the flash-light is adapted to project light into said housing substantially along the longitudinal axis, the other end wall of said housing remote from the light source having openings provided therein defining another signal legend adapted to be illuminated from inside said housing, a tube mounted in said housing on the longitudinal axis and adapted to conduct the major portion of the light from said flash-light to the other end of said housing, said tube being spaced at its ends from the end walls and being also spaced from the side walls so as to allow only indirect lighting of the signal legend openings in said side walls, and a plate mounted in said housing transversely relative to the outer end of said tube in spaced parallel relation between the outer end of said tube and the adjacent end wall so as to provide indirect lighting of the signal legend openings in said end wall and to reflect light toward the legend openings in said side walls.

6. In a portable hand signal light, a housing of elongated form having side walls uniformly spaced from a longitudinal axis, said housing also having opposed end walls, the side walls having openings provided therein defining signal legends adapted to be illuminated on their inner side, a light source, such as a flash-light, on one end wall of said housing arranged to project light into said housing substantially along the longitudinal axis, said flash-light providing an elongated handle projecting from the said end wall on said longitudinal axis, and a tube mounted in said housing on the longitudinal axis and adapted to conduct the major portion of the light from said flash-light to the other end of said housing, said tube being spaced at its ends from the end walls and being also spaced from the side walls so as to provide indirect lighting of the signal legend openings in said side walls, light issuing from the end of said tube being reflected toward the legend openings in said side walls.
